ADOLF ROHRBACH, OF CHARLOTTENBURG, GERMANY.

FLYING BOAT.

Application filed March 24, 1924, Serial No. 701,495, and in Germany June 21, 1920.

This invention relates to hydroaeroplanes and particularly to flying boats.

The object of the invention generally is to increase the lateral stability of the craft while floating and taxiing, to facilitate and expedite the operation of starting and emerging from the water and to reduce the power required for taking off. A further object of the invention is a flying boat in which the displacement of the boat may be substantially reduced as compared with prior flying boats with which I am familiar.

To these ends I have devised a flying boat including a special arrangement of central boat hull structure and side displacement floats, whereby the frontal and frictional resistances of the parts in the water are substantially reduced at starting and the bringing of the craft to the hydroplaning position may be quickly and easily effected, thereby rendering available an addition of energy or power for the taking off operation and substantially reducing the take-off distance and time as compared with prior flying boats.

According to my invention the flying boat is provided with two displacement and hydroplaning floats substantially centrally arranged on opposite sides of the central boat hull and in comparatively close proximity thereto, the boat extending below the level of the bottoms of the displacement floats. A great and positive metacentric height at rest and while taxiing is thereby secured for the craft, together with an increased dynamic lifting effect and reduction of resistances at starting. The displacement floats exert a positive lifting effect on the craft and after overcoming the critical speed they are gradually detached from the water, emerging therefrom prior to the emergence of the boat hull, the complete take-off of the boat being thereby expedited and facilitated.

In consequence of the arrangement of the two lateral floats close to the boat, the dimensions of the flying boat regarding its displacement can be considerably reduced as the lateral floats support at the state of rest and at the starting, a considerable part of the load. If the boat is running, the load resting upon the floats, diminishes at increasing speed and, in accordance with the increasing lifting power, this reduced load can now be easily carried by the flying boat of smaller dimensions. It is, however, necessary, to reduce with increasing relieving of the floats the frontal and frictional re-

sistances of the same in the water. With this object in view, the boat is constructed in such manner that, in the course of the starting from the water, the boat gradually becomes self-carrying, the floats reducing the resistances by gradual lifting.

The central arrangement of floats in close proximity to the boat combines the advantages of a flying boat with the advantages of a float-flying machine.

For a better understanding of the invention reference may be had to the accompanying drawings forming a part of this application wherein—

Fig. 1 shows the flying boat in front elevation,

Fig. 2 shows the flying boat as land-flying machine,

And Figs. 3 and 4 are side elevations of a flying boat embodying a modified form of my invention.

The drawing (Fig. 1) shows by way of example a twin-engined monoplane. The hull 1 of this machine is constructed boat-like. At either side of the hull a float 2, 3 is arranged, connected with the boat by hinged struts 4. The supporting stays 5, 6, extending towards the supporting planes, are attached to the struts 4. The floats 2 and 3 are displacement and hydroplaning floats and are substantially centrally disposed and in comparatively close proximity to the boat hull 1.

For the floats 2, 3 on the horizontal struts 4 wheels 7, 8 may be substituted (Fig. 2) so that the flying boat can be used as a land flying machine, the struts 4 being arranged as horizontal axles, as shown.

The process of the combined action of the boat and its lateral floats is taking place according to the following principles: The two floats arranged at the sides of the hull are comparatively small. Therefore they possess comparatively little weight and meet with little air-resistance. By the coordination of the two floats to the flying boat, the latter can be of smaller dimensions, so that its size need not be any bigger than the requirements for accommodation necessitate.

At the state of rest the floats produce a positive metacentric height so that the machine does not take an inclination as is the case with flying boats of known types. At increasing speed the planes begin to carry so that the boat and the floats will gradually emerge from the water. In consequence of

the different immersion of the floats with regard to the boat, the floats will get out of the water much sooner, this resulting in a reducing of the resistance in the water, because now only the hull carries. It is evident that consequently the critical speed will be attained much sooner than with all other known devices or constructions.

In order to attain these advantages, the floats may be situated at a different height from the boat, or they may be removed into the direction of the longitudinal axis of the flying machine, as for example illustrated in Figs. 3 and 4 of the drawing so that because of the inclination of the flying machine at the starting, they leave the water prior to the boat.

In Fig. 1 the supporting floats 2 and 3 are indicated as having their planing bottoms disposed above the level of the bottom of the boat 1 (the latter being diagrammatically illustrated), and this figure indicates the position of the craft at rest showing the floats 2 and 3 as emersed and carrying an appreciable portion of the weight of the craft. Figs. 3—4 show the floats 2' and 3' as slightly removed or displaced in the direction of the longitudinal axis of the craft from the median position thereof, whereby the tilting or inclination of the craft at starting about the median portion thereof elevates the floats and causes the emergence thereof prior to the emergence of the boat itself. For example, Fig. 4 indicates the position at starting when the floats 2', 3' are emerging from the water, the inclined or tilted position of the craft causing the elevation of the forwardly positioned floats and facilitating the prior emergence thereof. The center of pressure or buoyancy of the float 2', (3') is indicated as being approximately in the position 9 which is observed to be slightly forward of the center of gravity of the craft approximately indicated at 10. While the forward shifting of the floats 2' and 3' is the preferred arrangement, it is observed, as indicated above, that the advantages of the applicant's invention may be attained by having the displacement floats simply situated at a higher level than the boat body, but in this case for best results it is desirable that the displacement floats be arranged approximately midships of the boat hull, namely with their bows extending forward of the center of gravity 10 of the craft.

I claim:—

1. In a flying boat the combination of a main boat body of sufficient dimensions and displacement to contain therewithin the personnel compartment and to buoyantly and hydro-dynamically support the greater portion of the weight of the craft, with a pair of lateral supporting displacement and hydroplaning floats disposed on opposite sides

of the boat body with their bows extending forward of the center of gravity of the boat and adapted to hydrostatically and hydro-dynamically support an appreciable portion of the weight of the craft, and a supporting structure positioning and fixing the floats relatively to the boat so as to carry a definite and appreciable portion of the weight of the craft at rest, and upon starting to exert a positive lifting force upon the craft up to a certain critical speed but to emerge from the water prior to the emergence of the boat.

2. A flying boat of the character set forth in claim 1 wherein the side displacement floats are disposed in close proximity to the boat hull and their hydroplaning bottoms are disposed above the level of and entirely disconnected from the boat bottom.

3. In a flying boat a floating and hydroplaning structure including a main central elongated boat body and a pair of separate and distinct lateral supporting displacement and hydroplaning floats arranged on opposite sides of said main central boat body and in close proximity thereto, said floats being supported by the craft in a manner to carry an appreciable portion of the total weight of the craft both while at rest and during the early stages of the planing operation and having their centers of pressure disposed slightly forward of the center of gravity of the craft.

4. A flying boat of the character set forth in claim 1 wherein the side displacement floats are disposed intermediate the ends of the boat structure but displaced longitudinally of the boat from the median position thereof.

5. In a hydro-aeroplane, the combination of a lifting plane, with a floating and hydroplaning structure thereunder including a main central boat body of sufficient displacement to buoyantly and hydro-dynamically support the greater portion of the weight of the craft, a pair of separate and distinct lateral supporting displacement and hydroplaning floats disposed on opposite sides of the central boat body with their bows extending forward of the median position of the central boat body, said lateral floats being adapted to buoyantly and hydro-dynamically support an appreciable portion of the weight of the craft, and a supporting structure positioning and fixing the side floats relatively to the main central buoyant body so as to carry a definite and appreciable portion of the weight of the craft at rest and upon starting to exert a positive lifting force upon the craft up to a certain critical speed but to emerge from the water prior to the emergence of the boat.

6. In a flying boat a lifting wing, a power plant for propelling the craft during flight and a floating and hydroplaning structure

- therefor including a main central boat body of sufficient displacement to buoyantly and hydro-dynamically support the greater portion of the weight of the craft and a pair of 5 separate and distinct lateral supporting displacement and hydroplaning floats disposed on opposite sides of the main central boat body and in close proximity thereto with their bows extending forward of the median 10 position of the boat body, said lateral floats being supported by the craft in a manner to carry an appreciable portion of the weight of the craft while floating at rest and hydroplaning at speeds below a predetermined 15 value upon the water, whereby a large and positive metacentric height is obtained and the resistance to the propulsion through the water is caused to substantially decrease before the taking off speed is reached due to the lifting operation of the lateral floats and the inclination of the bow 20 of the boat.
7. In a flying boat the combination of a main boat body with lateral supporting displacement and hydroplaning floats disposed on opposite sides thereof, said floats being displaced slightly forward of the median position of the boat and being supported in a manner to carry an appreciable portion of 25
- the weight of the craft while floating at rest 30 and to exert a lifting force on the boat while attaining a taking off speed.
8. In a flying boat, the combination of a main boat body with a pair of supporting displacement and hydroplaning floats arranged on opposite sides thereof and with their bows extending forward of the median position of the boat, said floats being separate and distinct from the boat but being of a character and being supported in a manner to be immersed when the boat is immersed and to carry an appreciable part of the weight of the craft in cooperation therewith but to clear the water in advance of the boat during the taking off operation. 40 45
9. A flying boat comprising a boat body in combination with a pair of lateral floats, horizontal struts extending from the boat body and connecting the floats with the same, said struts being formed as axles on which wheels may be mounted, interchangeably with the floats.
10. A flying boat of the character set forth in claim 8 wherein the lateral displacement and hydroplaning floats are braced 55 both against the boat and the wings.

In testimony whereof I affix my signature.

DR. ADOLF ROHRBACH.
